EYEGLASS FRAME

James J. Harley, Philadelphia, Pa., assignor to Optics International Corporation, Philadelphia, Pa., a corporation of Pennsylvania

Continuation of design applications Ser. No. 82,170 and Ser. No. 82,173, Oct. 14, 1964. This application Apr. 11, 1966, Ser. No. 2,507

Term of patent 7 years

(Cl. D57—1)

FIG. 1

FIG. 4

FIG. 5

FIG. 6

FIG. 7

FIG. 8

FIG. 9

FIG. 10

FIGURE 1 is a front elevational view of an eyeglass frame showing my new design;

FIGURE 2 is a rear elevational view thereof;

FIGURE 3 is a top plan view thereof;

FIGURE 4 is a bottom plan view thereof;

FIGURE 5 is a side elevational view thereof;

FIGURE 6 is a front elevational view of another embodiment of the design shown in FIGS. 1-5;

FIGURE 7 is a rear elevational view thereof;

FIGURE 8 is a top plan view thereof;

FIGURE 9 is a bottom plan view thereof;

FIGURE 10 is a side elevational view thereof;

The side views not shown are mirror images of the side views shown in FIGURES 5 and 10, respectively.

This application is a continuation of my copending applications Serial Nos. 82,170 and 82,173, filed October 14, 1964 now abandoned.

I claim:

The ornamental design for an eyeglass frame, substantially as shown and described.
